UNITED STATES PATENT OFFICE

HENRY KIELBERG, OF MARTINS FERRY, OHIO, ASSIGNOR TO WHEELING STEEL CORPORATION, OF WHEELING, WEST VIRGINIA, A CORPORATION OF DELAWARE

ROOFING ROLL

Application filed July 31, 1929. Serial No. 382,524.

This invention relates to roofing rolls, and the primary object thereof is to provide an improved structure of roll which eliminates the usual connecting shank between the 5 heads of the roll.

A further object of the invention is to provide a roll structure wherein the sheet metal or other roofing material can be easily and quickly connected to the independent roll 10 heads.

A still further object of the invention is to provide a roll structure which is of simple construction and in which the heads thereof can be produced in a stamping operation.

15 In describing the invention in detail, reference is herein had to the accompanying drawings, in which—

Figure 1 is a front elevation, parts being shown in section, illustrating the manner in 20 which the roofing material is applied to the heads;

Figure 2 is a section on line 2—2, Fig. 1;

25 Figure 3 is a similar view showing the material in the final stage of its securement to the heads;

Figure 4 is an inner side elevation of one of the heads;

Figure 5 is an edge elevation of one of the heads, partly broken away and in section; 30 and—

Figure 6 is a top plan view of one of the heads.

In proceeding in accordance with the present invention, a pair of similar heads are 35 employed, each of drum-like formation, having a circular body 1 of dished disk form, providing a peripheral seat 2 disposed at a right angle to the plane of said body, said seat having less diameter than that of the periphery of the disk 1 and being formed 40 with struck-out pointed or V-shaped tongues 3. Said tongues 3 extend outwardly from the periphery of the seat 2 and are preferably located at diametrically opposite points, 45 as shown in Fig. 4. It will be understood, however, that the location of said tongues and the number thereof may be varied as desired.

50 Each of the disks 1 is formed with a pair of perforations 7, for a purpose now to be

described. Referring to Fig. 1 of the drawings, it will be noted that a housing or frame structure composed of spaced standards 5 is provided, a pair of face plates 9 being mounted on stub shafts 10 journaled in the standards 5. Said face plates 9 are provided with lugs or pins 8 which are adapted to engage in the perforations 7 of the heads. A pulley 6, driven by any suitable source of power, is secured to one of the shafts 10.

In operation, the heads are placed on the face plates, as shown in Fig. 1, and are held against outward movement relative to said face plates. One end of the sheet metal, or roofing material, R is first secured to one of the tongues 3 of each of the heads, and the tongues are then bent downwardly, as shown in Fig. 2, which clamps the end of the material against the seats 2.

Following the bending of the tongues 3, as above described, the heads are then given one-half revolution to bring the oppositely disposed tongues 3 in the position shown in Fig. 2 in which the tongues also pierce the material R, following which the last mentioned tongues are bent downwardly so that all the tongues occupy the position shown in Fig. 3. In this manner an end of the roofing material is effectively anchored to each of the heads, following which power is applied to 80 the pulley 6 to rotate the heads and metal upon the latter.

From the foregoing it will be seen that the resultant structure is similar to the usual roofing roll or spool, but is without the usual connecting shank connecting the spool heads. Thus, the invention enables the rolls to be formed in a more economical and expeditious manner and, at the same time, provides a roll which is possessed of the same strength and efficiency as the usual spool type of roll in which the heads are positively connected one to the other.

What is claimed is—

1. In a roofing roll, a pair of unconnected heads of drum-like form, radially outwardly struck tongues formed on each of said heads to engage through the inner end portions only of the roofing material and to be bent down into seated relation to said end por-

tion for anchoring said material, portions of said heads being adapted to be abutted by the opposite lateral edges of the material and said heads being held by said material in their properly spaced relation.

- 5 2. In a roofing roll, oppositely facing metallic heads, each head comprising a sheet metal body of dished-disk form providing a peripheral seat disposed at a right angle to the plane of the body, each seat having there-in outwardly struck tongues adapted to project through the inner end portion of the sheet material to be wound thereon and then to be bent down into clamping overlying relation to said end portion for anchoring said material in place, said heads being maintained in their proper relative positions by said material.

In testimony whereof, I affix my signature.

HENRY KIELBERG.
